UNITED STATES PATENT OFFICE.

GEORGE JOHNSTON, OF DETROIT, MICHIGAN.

DESIGN FOR AN EYEGLASS-GUARD.

SPECIFICATION forming part of Design No. 35,198, dated October 22, 1901.

Application filed September 9, 1901. Serial No. 74,865. Term of patent 14 years.

To all whom it may concern:

Be it known that I, GEORGE JOHNSTON, a citizen of the United States, residing at Detroit, county of Wayne, State of Michigan, have invented and produced a new and original Design for an Eyeglass-Guard, of which the following is a specification, reference being had to the accompanying drawings, which form a part of this specification.

10 Figure 1 is a view in side elevation of an eyeglass-guard, showing my new design. Fig. 2 is a view in front elevation. Fig. 3 is a view in plan.

As shown in the drawings, the leading or 15 material features of my design for an eyeglass-guard consist of an upright perforated

plate or bar *a*, having corrugations *b* upon its edges. A curved arm *c* is disposed as shown, projecting laterally and upwardly from the lower end of said plate or bar and 20 in line therewith in front elevation.

Having described my invention, what I claim as new, and desire to secure by Letters Patent, is—

The design for an eyeglass-guard, as herein 25 shown and described.

In testimony whereof I sign this specification in the presence of two witnesses.

GEORGE JOHNSTON.

Witnesses:

N. S. WRIGHT,
J. M. POLAND.
